Attn:

UNITED STATES PATENT OFFICE.

EDWARD G. WATKINS, OF GARDNER, MASSACHUSETTS.

DESIGN FOR CANE FABRIC.

SPECIFICATION forming part of Design No. 26,480, dated December 29, 1896.

Application filed November 27, 1896. Serial No. 613,711. Term of patent 7 years.

To all whom it may concern:

Be it known that I, EDWARD G. WATKINS, of Gardner, in the county of Worcester and State of Massachusetts, have invented and 5 produced a new and original Design for Cane Fabric, of which the following is a specification.

Reference is to be had to the accompanying drawing, forming a part of this specification, 10 which shows a piece of cane fabric with my design applied.

The leading feature of my design consists of the intersecting stripes *a* and *b*, of contrasting color from the body of the fabric, 15 forming polygonal-shaped figures in the body of the fabric, the stripes *a* being depressed to show the body of the fabric in the form of checks within the body of the stripes, except at the intersection of the stripes *a* and *b*, 20 while the stripes *b* show through the body of the fabric in the form of checks.

f represents a piece of cane fabric bearing my design, consisting of the intersecting stripes *a* and *b*, of contrasting color, forming the polygonal figures *f'*.

The stripes *a* are depressed to show the body of the fabric through the body of the stripes in the form of checks, while the stripes *b* show in a like manner through the body of the fabric.

I claim—

The design for cane fabric, as herein shown and described.

In testimony whereof I have signed my name to this specification, in the presence of 35 two subscribing witnesses, this 18th day of November, A. D. 1896.

EDWARD G. WATKINS.
